UNITED STATES PATENT OFFICE.

GREGORY SIMON, OF PITTSBURG, PENNSYLVANIA

SWING.

979,580.

Specification of Letters Patent. Patented Dec. 27, 1910.

Application filed September 1, 1910. Serial No. 579,968.

To all whom it may concern:

Be it known that I, GREGORY SIMON, a citizen of the United States of America, residing at Pittsburg, in the county of Allegheny and State of Pennsylvania, have invented certain new and useful Improvements in Swings, of which the following is a specification, reference being had therein to the accompanying drawing.

10 This invention relates to swings, and especially to that type of swings used upon lawns, in parks and playgrounds, and the invention has for its object to provide a swing that can be easily and quickly operated by the occupants thereof.

Another object of the invention is to provide a swing constructed principally of metal, it being preferable to use ordinary gas pipe, for the main frame of the swing.

20 With the above and such other objects in view as may hereinafter appear, the invention consists of the novel construction, combination, and arrangement of parts to be hereinafter specifically described and then claimed.

Reference will now be had to the drawings, wherein:

Figure 1 is a side elevation of the swing. Fig. 2 is an end view of the same. Fig. 3 is an enlarged vertical sectional view of a portion of the swing. Fig. 4 is an enlarged cross sectional view of a portion of the same. Fig. 5 is an enlarged side elevation of a portion of the same, and Fig. 6 is an elevation 35 illustrating the detail of the swing.

A swing in accordance with this invention embodies two A-frames suitably braced and connected together and from these A-frames is suspended a carrier adapted to be 40 oscillated between the A-frames either by a movement of the occupants of the carrier or through the medium of an operating lever arranged above the carrier. Two A-frames are employed, and each frame comprises 45 angularly disposed supports 1 having the lower ends thereof mounted in sockets 2 and provided with straps 3, said straps being connected by longitudinal tie rods 4. The upper ends of the supports 1 are provided 50 with coupling pieces 5 connected, as at 6, to coupling pieces 7, carried by longitudinal tie rods 8. The supports 1 adjacent to the upper ends thereof are provided with straps 9 and these straps are connected by angularly disposed tie rods 10 having turn-

buckles 11 whereby the rigidity of the tie rods can be increased.

The inner sides of the supports 1 adjacent to the coupling members 5 are provided with bearings 12, each bearing being held in place by a clevis 13. In the bearings 12 are arranged anti-friction balls 14 revolvably supporting the ends of rock shafts 15 journaled in said bearings. Mounted upon the rock shafts 15 contiguous to the bearings 12 are hangers 16 and pivotally connected to said hangers, as at 17, are suspension frames 18 having central off-set portions 19. The suspension frames 18 are connected by bars 19^a to the rock shafts 15 and the off-set portions of said frames are braced by tie rods 20. The off-set portions 19 are furthermore provided with hangers 21 and suspended from these hangers by rods 22 is a carrier 23 having suitable seats 24. The frames 18 are provided with hangers 25 and these hangers are connected by braces 26 to straps 27 slidably mounted upon the rods 22.

The tie rods 8 of the A-frames are connected by a transverse plate 28, said plate 80 being secured to the tie rods by clevises 29. The plate 28 intermediate the ends thereof is provided with a bearing 30 for a fulcrumed lever 31. One end of the lever 31 is connected by a cable 32 to one of the suspension frames 18, and the opposite end of the lever is provided with an operating cable 33 passing over a sheave 34 revolvably carried by the rock shaft 15 at the off-set end of the swing from the cable 32, the 90 operating cable 33 extending downwardly in proximity to the carrier 23, whereby the occupants of the carrier by pulling upon the operating cable 33 can swing the carrier in one direction and by allowing the operating cable to become slack, the carrier will swing in the opposite direction. To facilitate this movement of the carrier, the operating lever 33 is connected by a coiled spring 35.

The off-set portions 19 of the suspension frames 18 are braced by longitudinal tie rods 36.

From the foregoing it will be observed that a swing in accordance with this invention is exceedingly well braced, particularly the upper part thereof, which receives the stress and strain when the carrier is in operation.

While in the drawings there is illustrated 110

a preferred embodiment of the invention, it is to be understood that the structural elements thereof are susceptible to such changes as fall within the scope of the appended claim.

What I claim, is:

A swing comprising a pair of supporting frames suitably connected together, a pair of inwardly extending bearings secured to each of said frames, a transversely-extending rock shaft revolubly supported by each pair of bearings, a suspension frame pivotally mounted upon each of said rock shafts and having a centrally disposed offset portion, a tie-rod for bracing the upper end of each of said offset portions, a tie-rod for connecting one offset portion to the other, pairs of bars connected to the shafts and the suspension frames in proximity to their off-

set portions, a pair of rods suspended from the offset portion of each of said suspension frames, a carrier supported by each pair of rods, inclined braces connected to each pair of rods and their respective suspension frame to one side of said bars, a fulcrum lever mounted at the top of said supporting frames, means for connecting one end of said lever to the offset portion of one of the suspension frames, and an operating cable connected to the other end of said lever and depending below the other suspension frame.

In testimony whereof I affix my signature in the presence of two witnesses.

GREGORY SIMON.
